Leg Support Stand, pjxray.com, <https://pjxray.com/leg-support-stand-lgs-10.html> (Year: 2020).*Primary Examiner — Steven J Czyz(74) *Attorney, Agent, or Firm* — Larson & Larson, P.A.;
 Justin P. Miller; Frank Liebenow(57) **CLAIM**

I claim the ornamental design for a leg support stand, as shown and described.

DESCRIPTION

FIG. 1 is a perspective view of a leg support stand showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines depict portions of the article that form no part of the claimed design.
